UNITED STATES PATENT OFFICE.

OSCAR M. LEICH, OF GENOA, ILLINOIS, ASSIGNOR TO LEICH ELECTRIC COMPANY, OF GENOA, ILLINOIS, A CORPORATION OF ILLINOIS.

SPARK-PLUG.

1,375,851.

Specification of Letters Patent. Patented Apr. 26, 1921.

Application filed November 6, 1919. Serial No. 336,157.

To all whom it may concern:

Be it known that I, OSCAR M. LEICH, a citizen of the United States, residing at Genoa, in the county of De Kalb and State 5 of Illinois, have invented a certain new and useful Improvement in Spark-Plugs, of which the following is a full, clear, concise, and exact description, reference being had to the accompanying drawings, forming a 10 part of this specification.

My invention relates to spark plugs and more particularly to a spark plug which is adapted to be used to ignite the charge of a gasolene engine. Spark plugs of this nature 15 must be of substantial construction, positive in operation and must be so constructed as to insure sparking at all times under the voltages of the ordinary batteries used in connection with engines of this kind.

20 It is an object of the invention to provide a spark plug with means for aiding the discharge of the main spark across the spark gap.

It is a further object of the invention to 25 provide a spark plug which is so constructed that the electrodes can not easily get out of alinement and will therefore remain in proper adjustment after once being set.

It is a further object of the invention to 30 provide a spark plug which may be readily cleaned if soot or oil gathers on the plug as is usual in plugs of this kind. Other objects will be apparent from the detailed description of the spark plug I have disclosed 35 in the drawings. In the drawings I have disclosed one form of my invention which form is the best known to me at the present time. However, it is to be understood that by this specification and the accompanying 40 drawings I do not intend to limit myself to the specific construction disclosed. The descriptive words used herein are used in a merely descriptive sense and not in a limiting sense. The real nature and scope of the 45 invention disclosed is to be determined from the claims appended to this specification.

The same reference characters have been used to designate the same parts throughout the several views of the drawings wherein— 50 Figure 1 is a vertical section taken through my improved spark plug;

Fig. 2 is a horizontal section taken on line 2—2 of Fig. 1;

Fig. 3 is a top view of the plug shown in 55 Fig. 1.

In the drawings the reference numeral 10 designates the body or shell member of the spark plug which body member is provided with the usual wrench engaging surface. This body member is also provided with a 60 threaded portion 11 which is adapted to engage the threaded opening in the cylinder of the engine. The body member here shown is also provided with a shoulder 12 which engages the gasket which is inserted 65 between the engine and plugs of this kind. Of course, it will be understood that if plugs are formed with the standard pipe thread that the shoulder will not be present.

Contained within the body or shell member 10 is the insulating base 13 which is shaped approximately as shown in the drawings and has an enlarged shoulder portion 14 which rests upon the shoulder 15 within the body member 10. A gasket 16 70 is inserted between the body member 10 and the shoulder 14 as shown in Fig. 1. A second gasket 17 is placed above the shoulder 14 and this gasket is adapted to be engaged by the nut 18 which has exterior threads 75 which are adapted to engage interior threads near the upper end of the body member 10. The nut 18 is provided with the usual wrench engaging surface 19 whereby the nut may be removed from the 80 body member 10 in order that the porcelain may be removed or replaced. Extending centrally through the insulating base 13 is the central electrode 20. This electrode is provided with an enlarged screw threaded 85 portion 21 which fits into a recess 22 in the top of the insulating base 13. I also prefer to protect the top of the insulating base by means of a metallic cap 23 shaped as shown 90 in Fig. 1. The plate 23 is in electrical contact with the screw threaded portion 21 of the electrode 20. Positioned on the screw threaded portion 21 is the usual terminal engaging nut 24 which is so shaped that terminals of different kinds may be used. 95 A terminal having a flat connecting element may be inserted between the nut 24 and the plate 23. The terminal having a fork shaped connecting element may be engaged around the smaller portion of the nut. 100 A terminal having a cup shaped engaging element may be slipped over the nut in the usual manner.

In the lower end of the insulating base 13 is provided a recess 25 and the lower end 110

of the main electrode 20 extends through this recess and slightly beyond the end of the insulating base as shown in Fig. 1. The insulating base is provided as shown in Fig. 5 1 with an enlarged extremity 26 preferably shaped as shown. Surrounding this enlarged extremity is a metallic cap 27 which is provided with a star shaped opening 28 through which the end of the electrode extends. The edges of this opening are provided with projecting portions 29 which extend inwardly or toward the main electrode 20 but are spaced therefrom so that there will be no electrical connection between the 10 metallic cap and the electrode 20. The metallic cap is bent around the enlarged extremity 26 as shown in Fig. 1 so that no additional means is necessary.

The second main electrode 30 is shaped as 20 shown in Fig. 1 and is securely fastened to the metallic body member 10. The electrodes 20 and 30 form between them the usual spark gap 31. This gap will be adjusted to suit the conditions under which the 25 spark plug is to be used.

The operation of my spark plug is as follows: When current passes through the main electrode 20 it will jump across the gap 31 to the electrode 30. The resistance 30 at this gap is very great due to the compressed condition of the air or gas around the end of the plug at the time the discharge or spark is to occur. Because of this great resistance there is considerable lag in the 35 spark when the spark plugs of ordinary construction are used. My device eliminates this lag in the following manner. The metallic cap 27 is carried by the insulating base 13 and has no electrical connection with 40 any portion of the spark plug. When the main discharge or spark occurs between the electrodes 20 and 30 the metallic cap 27 becomes charged with electricity due to the fact that it is in close proximity to the parts 45 of the plug which form part of the circuit. The metallic cap 27 acts as an electric condenser and due to this condenser or capacity effect a discharge takes place between the metallic cap and the central electrode 20 50 in advance of the main spark or discharge. The metallic cap 27 may properly be called an auxiliary electrode. The discharge from this auxiliary electrode to the main electrode 20 although small and hardly visible with 55 the naked eye will produce ionization of the gap or air around the electrode 20 thereby increasing the number of ions in the main gap. Due to the presence of these ions a discharge of the main gap will be effected at 60 a considerably lower voltage or electrical pressure than that required by the ordinary spark plug.

The ignition systems of all cars depend on a readily rising wave of pressure and therefore require a higher voltage to jump a gap 65

of given length. This is due to the fact that when the normal break down voltage is reached the discharge does not take place immediately and the voltage will either have to be maintained for a time or rise 70 above the normal discharge value to the extent at which the discharge actually takes place. This phenomenon is called the "lag of the discharge." My improved spark plug provides means for the ionization of the 75 gas in the main spark gap causing the current to discharge at a lower voltage and thereby almost overcoming the lag of the discharge. This will allow for a longer period of discharge for each current wave 80 thereby supplying more energy or heat to each discharge. My improved plug provides better ignition and therefore causes the engine to run better and cause the plugs to remain free from carbon and oil deposits. 85

The auxiliary electrode 27 is substantial in construction and cannot be readily displaced. It may be easily cleaned and has no rough or protruding corners. The projections 29 are spaced only a slight distance 90 away from the main electrode 20. If the free end of the main electrode 20 is bent in any direction it strikes one or more of the projections 29 before it reaches the elastic limit of the metal of which the electrode is 95 made. The electrode will therefore spring back to its normal or central position. The auxiliary electrode therefore prevents any accidental or wilful bending of the exposed end of the electrode 20. The electrode and 100 cap therefore remain in their predetermined fixed relation and the space between the electrode and the projections 29 remains constant. The function and operation of the cap therefore remain unchanged. The cap 105 27 completely incloses and protects the end of the insulating base 13. If the insulating base and its electrode are removed and replaced there will be no chance for the main and auxiliary electrodes to get out of alignment. This is a decided advantage and improvement over the spark plug shown in my former application Serial No. 283,566, filed Mar. 19, 1919. The cap 27 being rigid cannot be bent as may occur with the auxiliary electrode 12 of the Radtke Patent No. 1,290,780 on which this plug is an improvement. The spark gap may be adjusted in the ordinary manner by bending the electrode 30 away from the electrode 20 or toward it as the case may require. 110 115 120

Having thus described my invention what I claim as new and desire to secure by United States Letters Patent is:

1. A spark plug of the character described comprising a metallic body member and an insulating base secured therein, a main electrode carried by said body member, a second main electrode carried by said insulating base and an auxiliary electrode carried by 130

said insulating base adjacent said main electrode and inclosing the end of said base, said two main electrodes being in juxtaposition whereby the main spark passes directly between them.

2. A spark plug of the character described comprising a body member and an insulating base secured therein, a main electrode carried by said body member, a second main electrode carried by said insulating base and spaced from said first electrode to provide a spark gap between them, and means carried by said insulating base for ionizing the gas and air adjacent said spark gap and adapted to prevent undue bending of the end of said second electrode.

3. A spark plug of the character described comprising a body member and an insulating base secured therein, a main electrode carried by said body member, a second main electrode carried by said insulating base and spaced from said first electrode to provide a spark gap between them, said two main electrodes being in juxtaposition whereby the main spark passes directly between them, and means carried by said insulating base for preventing bending of said second electrode.

4. A spark plug of the character described comprising a metallic body member and an insulating member, coöperating main electrodes carried respectively by said body member and said insulating base, and an auxiliary electrode carried by said insulating base for ionizing the gas or air adjacent the ends of said main electrodes, said auxiliary electrode substantially inclosing the end of said insulating base to thereby hold it firmly against displacement.

5. A spark plug of the character described comprising a metallic body member and an insulating member, coöperating main electrodes carried respectively by said body

member and said insulating base, said two main electrodes being in juxtaposition whereby the main spark passes directly between them, and an auxiliary electrode carried by said insulating base for preventing bending of the free end of one of said main electrodes.

6. A spark plug comprising an insulating base having a recess in one of its ends, an electrode extending through said insulating base and having its free end projecting into said recess, a metallic cap secured to the end of said insulating base and spaced from the free end of said main electrode so as to prevent bending of said end in said recess beyond its elastic limit.

7. A spark plug of the character described comprising a metallic body member and an insulating base secured within said body member, coöperating main electrodes carried respectively by said body member and said insulating base, and means adjacent said electrode for ionizing the gas or air between said electrodes, said means also preventing bending of one of said electrodes.

8. A spark plug comprising a metallic body member, an insulating base positioned within said body member, a removable nut for securing said insulating base within said body member, a main electrode carried by said body member, a second main electrode extending through said insulating base and terminating adjacent said first electrode, and a condensing element carried by and inclosing the end of said insulating base and spaced from said second named electrode by a slight air-gap to thereby prevent bending of said second main electrode beyond its elastic limit.

In witness whereof I hereunto subscribe my name this 4th day of November, A. D. 1919.

OSCAR M. LEICH.
